UNITED STATES PATENT OFFICE.

EDWARD R. MONROE, OF BAY CITY, MICHIGAN.

PAPER-TUBE-MAKING MACHINE.

1,118,212.

Specification of Letters Patent. Patented Nov. 24, 1914.

Application filed April 16, 1913. Serial No. 761,449.

To all whom it may concern:

Be it known that I, EDWARD R. MONROE, a citizen of the United States of America, residing at Bay City, in the county of Bay 5 and State of Michigan, have invented certain new and useful Improvements in Paper-Tube-Making Machines; and I do hereby declare the following to be a full, clear, and exact description of the invention, such 10 as will enable others skilled in the art to which it appertains to make and use the same.

My invention relates to paper tube-making machines, and its objects are to provide 15 a machine of that character improved in various respects; also to provide such a machine which shall contain, in various combinations, already-existing or my newly-invented parts and devices of such machines:—all as hereinafter appearing; and in general, to provide such a machine, and such parts and devices thereof, which shall be simple and economical in construction 20 and easy and effective in operation. These objects are attained by, and my invention finds a preferable embodiment in, the structure hereinafter described and illustrated by the accompanying drawings, in which:—

Figure 1 is a side elevation of my paper 25 tube-making machine; Fig. 2 is a transverse vertical section thereof on line 2—2 of Fig. 1; Fig. 3 is a plan view of the same; Fig. 4 is a detail view in perspective of the tube-rolling members and connected parts, certain parts being broken away; Fig. 5 is a like view of portions of the same partially 35 in section on the line y—y; Fig. 6 is a detail view in vertical section of parts of the tube-discharging devices, with portions broken away; Fig. 7 is a diagrammatic view, in a transaxial plane, of certain driving gears of my machine; Fig. 8 is a detail view in perspective of a portion of the tube-rolling shaft; Fig. 9 is a like view of the end of a 40 finished tube; Fig. 10 is a like view of a retaining member for the paper tube-rolling pipe; and, Fig. 11 is a like view of a ratchet operating in connection with the feed-driving rack 29 and its gear 31.

On the main frame 1 is carried by suitable supports 5 and 6, a table comprising end portions 2 and 3 and a removable inter-

mediate portion 4, the support 6 being adjustable on the frame as by a bolt 100 so that, when it is desired to form a paper 55 tube of more or less paper, a wider or narrower table portion 4 may be inserted into the machine, the end portion 3 being movable to the left or to the right of Fig. 1 to accommodate such intermediate portion 60 and being then clamped on the frame by said bolt.

A roll of paper 9, turning on a shaft 8 carried by a suitable bracket 7, is unwound by the feeding rolls 13 and 14 connected by 65 gears 32 and 33 between which the paper passes after being properly tautened by a suitable tension roll 10 whose journals 11 are carried by arms 12 pivoted on the frame. After being trimmed to a true transverse 70 edge by manual operation of the knife 15, the paper is fed by the feed rolls (toward the right in Fig. 1) driven by suitable means, such as a belt (not shown) engaging the pulley 16 on the driving shaft 17 which 75 carries a mutilated gear 18, having teeth to mesh with the gear 21 on the shaft 22 which carries a disk 23 provided with a wrist pin and its anti-friction roller 24 which, moving in a longitudinal slot, in the arm 25 pivoted at 26 and thus reciprocates the rod 28 adjustably pivoted at 27 to the arm, and also pivoted to a rack 29. This rack reciprocates in a bearing block 30 and meshes with a pinion 31 on the shaft of the feeding 80 roll 14, thus rotating said roll to feed the paper. The mechanism is adjusted so as to rotate the feeding rolls a sufficient number of revolutions to feed the paper under the knife 15, over the table 2, 3, and 4 and between guides 35, to the tube-rolling members. Suitable pawls 101 are provided in the pinion 31 (see Fig. 11) engaging a ratchet in the shaft 34^a to permit the upward or return movement of the rack bar without 95 rotating the feeding roll backward.

A cam disk 38 carried by the driving shaft 17 is so adjusted thereon that, as soon as the paper is fed beyond a horizontal transversely-arranged glue pipe 37 adjustable in 100 brackets 36 somewhat more than the length of paper required to make one turn of the paper tube, the plunger 39 is moved by said cam to open a suitable valve 40, thus per-

mitting the glue under pressure to flow from a pipe 40^a (connected to a supply source not shown) and in a spray onto the paper for nearly its remaining length necessary to 5 form the paper tube; whereupon the cam permits the valve 40 to close under the pressure of the spring 102. The paper is thus coated with glue, and its forward edge guided by means of a roller 74 and fingers 73 10 on the edge of the table 2 is fed into the longitudinal slot 43 through the wall of the tube-forming pipe 42 and also into the registering longitudinal groove 45 in the co-operating tube-forming shaft 44 having a 15 limited relative rotative movement inside the pipe and supported in bearings 46 and 47 at one end and on the movable bearing 70^a at the other end. The teeth of the gear 18 having now passed out of mesh with the 20 gear 21, and before they are carried into mesh with the gear 19, the cam 50 carried by the driving shaft 17 is turned to a position which allows the cam lever 51 to rise under tension of the spring 88, a connecting 25 rod 53 being pivoted to the cam lever and to a lever 103 fixed on a rock shaft 54, whereby said lever withdraws the wedge 52 from its previous position between the arm 56, fixed on the shaft 44 and the arm 55 fixed on the 30 pipe 42; as the wedge is thus withdrawn the spring 57 draws these arms toward each other, thus throwing the slot 43 and groove 45 out of their registration and clamping the end of the paper between the shaft 44 35 and pipe 42 and swings the roller 86 against the pipe 42, such parts now occupying the position shown in Fig. 5.

A cam disk 85 carried by the driving shaft 17 moves the cam lever 82 pivoted at 72 40 downwardly, which through the connecting rod 83 forces downwardly and against the pressure of a spring 80 the bar 79 reciprocable in a bearing block 104 adjustable on the frame in any convenient manner: This 45 bar carries the transversely-arranged horizontal bar 77 and its knife 15, which by this movement severs from the roll the length of paper required for one tube. Small punches 78 may be carried by the bar 77 and 50 sufficiently in advance of such knife to punch suitable devices, as the name of the owner, etc., through the part of the paper which is to form the outside turn of the tube.

The teeth of the gear 18 being now carried 55 into mesh with the gear 19 on the shaft 20, the gear 49 on said shaft rotates the gear 48 on the shaft 44, whereby the length of paper is wound around the pipe 42 and, being pressed by the roller 86 carried by arms 87 60 on the rock shaft 54, the paper tube is formed around the pipe 42. This done, the teeth of the gear 18 now pass into mesh with the gear 21 on the shaft 22 which shaft carries a bevel gear 59 meshing with a gear 60

on a shaft 61 journaled in a bracket 62 and carrying a crank wheel 63 connected by a rod 65 to a bell-crank lever 64, carrying a segmental gear 58 meshing with a pinion 66 on the shaft 67 journaled in a bracket 68. A gear 69 on this shaft meshes with a rack bar 70 70^a slidable horizontally in guides 71 (see Fig. 6). This rack bar carries an arm 70^b encircling the pipe 42 and a conical bearing 70^a fitting into and supporting the spindle 44 during the tube-rolling operation, and 75 carried away from the same when the tube is removed as hereinafter described. This rack 70 is moved outwardly (to the left hand in Fig. 2) by the above described movement of the segmental gear 58 and pushes the completed paper tube off the pipe 42; and as the gear 21 makes one revolution the rack has returned to its original position, and during this revolution of said gear 21 the paper has been fed forward to the position for rolling 80 another tube.

The pipe 42 is retained in place while the paper tube is being removed therefrom, by a suitable retaining member 90 (shown in Figs. 4 and 10) detachably fastened to the 90 shaft 44 by a collar 56 and having an overhanging portion as shown adapted to engage and hold the pipe 42 against longitudinal movement only. Such pipes 42 of various 95 external diameters may be provided, all however, being adapted to fit internally around the shaft 44, and their inner ends being turned down to a uniform size, any one may be attached to my machine by the retaining member 90: paper tubes of different diameters may thus be formed. When the length 100 of paper to make a paper tube is to be greater or less, the bearing block 104 and support 6 may be moved along the frame to a corresponding adjustment by any 105 convenient means.

Not confining myself to details of construction shown or described, I claim:

1. In a machine of the character described, 110 a frame, tube forming means mounted in the frame comprising a tubular member having a longitudinal slot, a shaft rotatably mounted in the tubular member and having limited rotative movement relative thereto and provided with a longitudinal groove 115 adapted to register with said slot of the tubular member, an arm connected to the tubular member, an arm connected to the shaft opposite to the arm of the tubular member, means to hold said arms normally separated so as to maintain said groove and slot in alignment so that the end of the paper may pass through the slot into the groove, means to operate said holding means to release said arms, means to force the arms toward each other when said holding means is released from engagement therewith so as 120 to rotate the tubular member and shaft 125

slightly relative to each other and thereby fasten the paper in said groove of the shaft.

2. In a machine of the character described, a frame, tube forming means mounted on the frame comprising a tubular member having a longitudinal slot, a shaft rotatably mounted in the tubular member and having limited rotative movement relative thereto and provided with a longitudinal groove adapted to register with said slot of the tubular member, a pair of oppositely disposed normally spaced arms one connected to the tubular member and the other connected to said shaft, means adapted to engage said arms to separate the same and hold them normally separated so as to maintain said groove and slot in alinement so that the end of the paper may pass through the slot into the groove, means for shifting said arm holding means out of co-operative engagement with said arms, means to force the arms toward each other when said holding means is shifted from between the arms so as to rotate the tubular member and shaft slightly relative to each other and thereby fasten the paper in said groove of the shaft and means for ejecting the finished tube therefrom.

3. In a machine of the character described, a frame, tube forming means mounted on the frame comprising a tubular member having a longitudinal slot, a shaft rotatably mounted in the tubular member and having limited rotative movement relative thereto and provided with a longitudinal groove adapted to register with said slot of the tubular member, an arm connected to the tubular member, an arm connected to the shaft, means between said arms to hold them normally separated so as to maintain said groove and slot in alinement so that the end of the paper may pass through the slot into the groove, means to shift said arm holding means from between said arms, means to force the arms toward each other when said holding means is shifted from between the arms so as to rotate the tubular member and shaft slightly relative to each other and thereby fasten the paper in said groove of the shaft, and means for ejecting the finished tube therefrom.

4. In a machine of the character described, a frame, tube forming means mounted on the frame comprising a tubular member having a longitudinal slot, a shaft rotatably mounted in the tubular member and having limited rotative movement relative thereto and provided with a longitudinal groove adapted to register with said slot of the tubular member, an arm connected to the tubular member, an arm connected to the shaft, means between said arms to hold them normally separated so as to maintain said groove and slot in alinement so that

the end of the paper may pass through the slot into the groove, means to shift said arm holding means from between said arms, means to force the arms toward each other when said holding means is shifted from between the arms so as to rotate the tubular member and shaft slightly relative to each other and thereby fasten the paper in said groove of the shaft, means for rotating the tubular member and rolling the paper thereon, a collar slidably embracing the tubular member to engage one end of the tube, and means for sliding the collar on the tubular member to eject the finished tube therefrom.

5. In a machine of the character described, a frame, tube forming means mounted on the frame comprising a tubular member having a longitudinal slot, a shaft rotatably mounted in the tubular member and having limited rotative movement relative thereto and provided with a longitudinal groove adapted to register with said slot of the tubular member, an arm connected to the tubular member, an arm connected to the shaft, means between said arms to hold them normally separated so as to maintain said groove and slot in alinement so that the end of the paper may pass through the slot into the groove, means to shift said arm holding means from between said arms, means to force the arms toward each other when said holding means is shifted from between the arms so as to rotate the tubular member and shaft slightly relative to each other and thereby fasten the paper in said groove of the shaft, means for rotating the tubular member and rolling the paper thereon, a rack slideable on the frame, an arm connected to the rack and having slideable connection with the tubular member, and means to slide the rack and thereby shift the arm connected thereto to eject the finished tube from the tubular member.

6. In a machine of the character described, a frame, tube forming means mounted on the frame comprising a tubular member having a longitudinal slot, a shaft rotatably mounted in the tubular member and having limited rotative movement relative thereto and provided with a longitudinal groove adapted to register with said slot of the tubular member, an arm connected to the tubular member, an arm connected to the shaft, means between said arms to hold them normally separated so as to maintain said groove and slot in alinement so that the end of the paper may pass through the slot into the groove, means to shift said arm holding means from between said arms, means to force the arms toward each other when said holding means is shifted from between the arms so as to rotate the tubular member and shaft slightly relative to each

other and thereby fasten the paper in said groove of the shaft, means for rotating the tubular member and rolling the paper thereon, a rack slidable on the frame, an arm 5 connected to the rack and having slidable connection with the tubular member, a pinion meshing with the rack, a toothed segment swingingly mounted on the frame and operated by said pinion, a shaft journaled 10 in the frame, means for rotating said shaft, and means between the shaft and said toothed segment to swing the same and thereby operate the rack to eject the finished tube from the tubular member.

15 7. In a machine of the character described, a frame, tube forming means mounted on the frame comprising a tubular member having a longitudinal slot, a shaft rotatably mounted in the tubular member and 20 having limited rotative movement relative thereto and provided with a longitudinal groove adapted to register with said slot of the tubular member, an arm connected to the tubular member, an arm connected 25 to the shaft and disposed opposite the aforesaid arm, a rod connected to one arm and extending through and projecting beyond the other arm, a spring on the projecting end of said rod adapted to force said arms 30 normally toward each other, means arranged to engage between said arms to hold them normally separated so as to maintain said groove and slot in alinement so that the end of the paper may pass through the slot into 35 the groove of the shaft, means to shift said means which engages between the arms from between the latter so that the latter may move toward each other and thereby rotate the tubular member and shaft slightly relative to each other and thereby fasten the 40 paper in said groove of the shaft, and means for rotating the tubular member and rolling the paper thereon.

8. In a machine of the character described, a frame, tube forming means mounted on the frame comprising a tubular member having a longitudinal slot, a shaft rotatably mounted in the tubular member and having limited rotative movement relative 50 thereto and provided with a longitudinal groove adapted to register with said slot of the tubular member, an arm connected to the tubular member, an arm connected to the shaft and disposed opposite the aforesaid arm, a rod connected to one arm and extending through and projecting beyond the other arm, a spring on the projecting end of said rod adapted to force said arms 55 normally toward each other, means arranged to engage between said arms to hold them normally separated so as to maintain said groove and slot in alinement so that the end of the paper may pass through the slot into the groove of the shaft, means to shift said

means which engages between the arms from 65 between the latter so that the latter may move toward each other and thereby rotate the tubular member and shaft slightly relative to each other and thereby fasten the paper in said groove of the shaft, and means 70 for rotating the tubular member and rolling the paper thereon, means to press the paper as it is rolled into tubular form, means for shifting said pressing means automatically into and out of operative position, and 75 means for ejecting the finished tube from the tubular member.

9. In a machine of the character described, a frame including a table, tube forming means mounted on the frame adjacent one end of the table and comprising a tubular member having a longitudinal slot, a shaft rotatably mounted in the tubular member and having limited rotative movement relative thereto and provided with a 80 longitudinal groove adapted to register with said slot of the tubular member, a guide leading from the table to a point adjacent the slot of the tubular member, an outwardly extending arm connected to the tubular member, an outwardly extending arm connected to the shaft, means to engage between the arms to hold them normally separated so as to maintain said slot and groove 85 in alinement so that the end of the paper 90 may pass over said guide through the slot of the member into the groove of the shaft, means to shift said means which extends between the arms, means to force the arms toward each other, when said means which 95 engages between them is shifted from between the same and thereby rotate the tubular member and shaft slightly relative to each other and fasten the paper in said 100 groove of the shaft, means for rotating the 105 tubular member and rolling the paper thereon, and means for ejecting the finished tube therefrom.

10. In a machine of the character described, a tube forming means mounted on a frame comprising a tubular member having a longitudinal slot, a shaft rotatably mounted in the tubular member and having limited rotative movement thereto and provided with a longitudinal groove adapted 110 to register with said slot of the tubular member, an arm connected to the tubular member, an arm connected to said shaft, said arms being arranged opposite each other, swinging means to engage between 115 said arms to hold them normally separated so as to maintain said groove and slot in alinement so that the end of the paper may pass through the slot into the groove, means for swinging said holding means from between said arms, yieldable means to force 120 the arms toward each other when said swinging holding means is swung from between 125

the arms so as to rotate the tubular member and shaft slightly relative to each other and thereby fasten the paper in said groove of the shaft, means for rotating the tubular member and rolling the paper thereon, and means for ejecting the finished tube therefrom.

In testimony whereof I affix my signature in presence of two witnesses.

EDWARD R. MONROE.
